UNITED STATES PATENT OFFICE.

ROBERT W. HARE, OF ALLEGHENY, PENNSYLVANIA.

ELEVATOR.

SPECIFICATION forming part of Letters Patent No. 521,086, dated June 5, 1894.

Original application filed August 31, 1893, Serial No. 484,462. Divided and this application filed May 12, 1894. Serial No. 511,041. (No model.)

To all whom it may concern:

Be it known that I, ROBERT W. HARE, a citizen of the United States, residing at Allegheny, in the county of Allegheny and State of Pennsylvania, have invented certain new and useful Improvements in Elevators, of which the following is a specification, reference being had therein to the accompanying drawings.

This invention relates to certain new and useful improvements in fire doors to cover the hatch-ways of elevators.

The object of the invention is to provide novel means whereby the doors of several floors may be carried on top of the elevator car, and stored at the top of the elevator shaft; furthermore, to so construct all the parts of the mechanism that the operation of storing the doors on the supports and releasing the same, will be entirely automatic.

With these objects in view the invention consists in novel combinations and arrangements of parts to be hereinafter more particularly described and specifically pointed out in the claims.

The machine is especially designed and adapted to be used on side-post elevators, yet with slight changes it may be operated on those having corner posts.

The invention is also particularly applicable to elevators of high speed, but it can be operated equally as well on slow speed or freight elevators.

In describing the invention in detail reference is had to the accompanying drawings, forming part of this specification, in which like numerals of reference indicate corresponding parts in the several views, in which—

Figure 1 is a view in front elevation of an elevator shaft, showing the doors landed in position at their respective floors. Fig. 2, is a similar view showing the doors resting on the hangers at the top of the elevator shaft. Fig. 3, is a view in side elevation partly in section, showing the arrangement of the door hangers, the supports for the doors and their operating mechanism on the car being omitted. Fig. 4, is a detail view of the releasing mechanism arranged to the side-post of the elevator shaft. Fig. 5, is a view in side elevation representing the mechanism of the sliding bar retracted and showing in dotted lines

the position of the same when retracted. Fig. 6, is an enlarged detail view of the mechanism arranged to the side post of the elevator shaft corresponding with Fig. 4, but more clearly illustrating a different position.

In the drawings 1, represents the side posts of an elevator shaft; 2, the elevator car; 3, the fire doors; 4, the guides attached to the sides of the elevator car for the reception of the adjustable upright standards or supports 5, which form a support for the doors while riding with the elevator car, said supports being adjustable through a horizontal lever 6, pivotally secured at 7, to the sides of the elevator car, while at its opposite end an arm 8, is secured, which has notches 9, 10, for the reception of the stationary pin 11. To the horizontal lever 6, are pivotally secured near its center, links 12, forming a V and carrying levers 13 fulcrumed at 14 and engaging the said supports 5.

The numeral 21, represents a recess in one of the side posts which contains the spring 22, pivoted at 23, and working against a spiral spring 25, and a bolt 26, extending and operating through an aperture 27, in the side post; embracing the side posts are anti-friction guides 28 and 28 $\frac{1}{2}$, having rollers 29, and inwardly extending portions 30; on the outer face of the guide 28 is a transverse slot 31, also a hinged support 31 $\frac{1}{2}$, which operate in conjunction with the guide, which also carries on its outer face links 32, forming with the links 33, a diamond as shown in dotted lines (Fig. 5) of the drawings. These links 32, are secured together by a pivot 34, said pivot extending into and being movable in the slot 31. At the opposite end the links 32, are pivoted to other links 33, as at 35, and also to the supports 36, which operate through guides 37, rigidly attached to the sides of the elevator shaft; the supports are bent at right angles, as shown at 38, and have on their top surfaces pins 39. The links 33, have at their free ends slots 40, and are pivoted together and to the side posts 1, as shown at 41.

The series of doors are arrested at the various landings by a system of differential blocks, which is the usual mode of supporting doors of this class.

For the purposes of a clear explanation as

to the *modus operandi* of this device, let us suppose the doors are all in position at the landings (as shown in Fig. 1, of the drawings) and it is desired to place them on the supports. The door supports on the elevator car are raised to the maximum limit by the engagement of the pin 11, with the notch 9, of the arm 8, when the elevator car is started, and as the supports come in contact with the doors which ascend on top of the standards or supports, the doors are carried to the top of the shaft and while ascending, the top floor comes in contact with the anti-friction guides 28 which retract the supports 36, and the side 15 of the elevator car depresses the spring 22, which is arranged in the path of its travel and thus forces the bolt 26 out through the side post and forms a seat for the hinged support, the latter riding above the bolt. When 20 the elevator car reaches this point the doors are above the supports 36, and the latter having been retracted so as to pass under the doors as described above, on the ascent of the car door, as the elevator car is lowered, secure the doors. The supports 36, are prevented from returning to their normal position at this time on account of the support 31 $\frac{1}{2}$, resting on the bolt 26. The lower door is provided with apertures in its under side 25 for the reception of the pins 39, on the supports 36, preventing lateral motion of the said supports. As the elevator car descends in its course below the spring 22, the spiral spring 25, which has been depressed takes its normal 30 position forcing the spring 22, inwardly and with it the bolt 26, which forms the rest for the hinged support 31 $\frac{1}{2}$; this will allow the latter to drop a short distance as illustrated in Fig. 4, while the doors are held in position on the 35 support by the force of gravity and the pins 39 heretofore referred to, while the elevator car returns to the ground floor and the supports 40 thereon are lowered to a position level with the beam of the elevator car. While so adjusted, the car may run up or down without disturbing the doors, it being understood that a stop is secured on the operating cable at a suitable distance from the top to prevent the car ascending sufficiently to disturb 45 the doors when the supports 5 on the car are lowered. When it is desired to close the opening on the elevator shaft, the supports are adjusted to the next notch 10, and the elevator car ascends to the top floor of the 50 building, engages the doors and lifts them

above the supports. The guides 28 however with this adjustment are not raised far enough to bring the lower edge of the support 31 $\frac{1}{2}$, above the bolt 26. The supports 36, retract automatically by reason of the gravity of the mechanism, after the supports are removed, the doors are allowed to descend with the elevator car and at the several landings are arrested as heretofore explained. The entire operation is simple and wholly automatic. 65

Particular attention is called to the fact that in an emergency, or in case of conflagration, the elevator car may be run to the top of the building to carry down the doors without the aid of a person accompanying the elevator car. 70

It will be understood that various changes may be made in the detail construction of this device without departing from the general idea involved. 75

An application filed by me August 31, 1893, Serial No. 484,462, contained a description of the device herein claimed, this application being a division thereof.

Having fully described my invention, what I claim as new, and desire to secure by Letters Patent, is—

1. In an elevator, the combination with a car having adjustable supports or standards adapted to carry a series of doors, of a device 80 for supporting said doors at the top of the shaft, and means for automatically extending and automatically withdrawing said device when the doors are raised from engagement therewith, substantially as described. 85

2. In an elevator, the combination with a car having supports or standards, of a series of hatch doors adapted to be carried thereby, a device for storing said doors at the top of the shaft, and means for automatically retracting and automatically extending the device, substantially as described. 95

3. In an elevator, the combination with a car, of a series of hatch doors adapted to be carried on the top thereof, a device at the top 100 of the shaft adapted to receive the doors, and means for automatically retracting and automatically extending said device, for the purpose described.

In testimony whereof I affix my signature in presence of two witnesses.

ROBERT W. HARE.
